SURFACE ORNAMENTATION OF WALLS.

No. 18,425.

Patented July 3, 1888.

Fig. 3.

Fig. 2.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,425, dated July 3, 1888.

Application filed March 17, 1888. Serial No. 267,572. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

In the accompanying photographs, Figure 1 represents my design in a single row; Fig. 2, 15 the same in two rows, and Fig. 3 the same in multiple rows.

Similar letters of reference indicate like parts.

A is a quadrangular elevation having inclined or beveled edges, as B. Upon the face of said elevation A appears an elevation, B, having four rounded faces, as C D E F. Upon the elevation B appears an elevation, C, also having four rounded surfaces, as G H I J,

which meet at an apex. Disposed parallel to the sides of elevation A are four elongated elevations, K L M N, having rounded upper surfaces and beveled extremities. Interposed at the corners of the design and between the elevations K L M N are four pyramidal elevations, O P Q R, having convex or outwardly rounded sides. Between elevations A and K L M N and O P Q R appear channels S T and U V.

I claim—

The design for surface ornamentation of walls, &c., substantially as herein shown and described.

FREDERICK KOSKUL.
